UNITED STATES PATENT OFFICE.

EUGENE B. CROCKER, OF PAWTUCKET, RHODE ISLAND.

EASEL.

SPECIFICATION forming part of Letters Patent No. 338,165, dated March 16, 1886.

Application filed October 21, 1885. Serial No. 180,474. (No model.)

To all whom it may concern:

Be it known that I, EUGENE B. CROCKER, of Pawtucket, in the county of Providence and State of Rhode Island, have invented certain new and useful Improvements in Easels, of which the following is a full, clear, and exact description, reference being had to the accompanying drawings, forming part of this specification.

15 My invention relates to folding easels, and has for its object the provision of an easel that is readily folded and adjusted, and all parts of which are permanently fixed together.

To the above purpose my invention consists in the peculiar arrangement and construction of the shelf, brace, and side supports of the easel, as hereinafter described and claimed.

In the accompanying drawings, Figure 1 20 represents a front elevation of the easel folded. Fig. 2 represents a front elevation of the easel opened and adjusted. Fig. 3 represents a side elevation of Fig. 2.

In the drawings like letters designate like parts.

25 The side supports consist of rods bent U-shaped at *a* and crossing one another at the points *c d e*, as shown in Figs. 1 and 2, where they are made fast, and at the point *h*, where 30 they are loose. The brace-rod *s* has its foot bent into a snap-hook, *k*, and at a point, *h'*, above its center, it is loosely flexed around the rods of the side supports (in a loop perpendicular to the axis of the said rod) at the point *h*, forming a free joint. The cross-rod *r* is made fast to the front of the side supports at equal distances above the bends *a a*. The prop *p* is a V-shaped rod having its free ends loop-hinged around the cross-rod *r*, just within

the bends *a a*, and hooked at *l l*, forming the 40 shelf for the easel, and adapted to take into the snap-hook *k* at its apex to prop the brace 45 *s* when the easel is adjusted, as shown in Figs. 2 and 3, and adapted to be folded up, as shown in Fig. 1, when the easel is folded. The cylindrical-shaped bodies *t t* are merely ornaments borne on the free ends of the support-rods. Of course the side supports are in their functions constructively single rods, though only shown as double, being bent at *a*.

50 Having thus described my invention, I claim as new and desire to secure by Letters Patent—

1. An easel having the side supports crossing above their centers, and around which crossing is looped the brace-rod, and having 55 said side supports fixedly connected near their bases by a cross-rod, to which is hinged a V-shaped prop-rod, for the purpose described.

2. A folding easel having the side supports crossing above their centers, and around which 60 is looped the brace-rod, and having said side supports fixedly connected near their bases by a cross-rod, to which is hinged a V-shaped prop-rod, the bent free ends of said prop forming the shelf of the easel when adjusted, for the 65 purpose described.

3. The combination, with the side supports bent at *a* and having the cross-rod *r*, of the brace-rod *s*, having a snap-hook, *k*, and looped at *h'* around said side supports, and of the 70 prop-rod *p*, having the bent ends *l l*, and hinged to said rod *r* and taking into the snap-hook *k*, for the purpose described.

EUGENE B. CROCKER.
